FIBER CAN TREATING MACHINE

Llewellyn Biggs, Leonia, N. J., assignor to American Can Company, New York, N. Y., a corporation of New Jersey

Application November 20, 1940, Serial No. 366,471

6 Claims. (Cl. 93—36)

The present invention relates to a fiber can treating machine and has particular reference to an apparatus which operates on a fiber container or can for temporarily holding a hinged closure element in closed position in the top wall of the can.

In a fiber container of the type disclosed in the John M. Hothersall Patent 2,085,979, issued by the United States Patent Office on July 6, 1937, the empty can is temporarily sealed or closed by insertion of a drawn plug closure element. Such sealed condition is maintained until the container is to be filled with its contents. This is a sanitary measure taken to insure against contamination of the contents which in the case of the said patent is milk or milk products.

The present invention embodies a simple high speed apparatus which functions to more positively keep such an empty fiber container temporarily closed until it is time to fill it with its contents and this invention contemplates a slight reforming of certain parts of the inserted closure element for that purpose.

An object of the present invention is the provision of an apparatus having mechanism for continuously advancing empty containers with hinged closure elements through an expanding operation during which time the inserted closure elements are temporarily fastened in substantially secure holding position.

A further object of the invention is the provision of an apparatus of the character described which embodies a rotatable turret for receiving and for holding the containers in certain positions during their travel so that the closure element of each container is reshaped to more positively hold it in can closing position.

Another object of the invention is the provision in such an apparatus of expanding fingers associated with each turret pocket so that different containers may be treated at the same time and while they are being continuously advanced by the turret.

Numerous other objects and advantages of the invention will be apparent as it is better understood from the following description, which, taken in connection with the accompanying drawings, discloses a preferred embodiment thereof.

Referring to the drawings:

Figure 1 is a plan sectional view of an apparatus embodying the present invention and showing the empty closed containers being advanced and operated on to effect the desired holding of the closure elements;

Fig. 2 is a vertical transverse sectional view

taken substantially along the broken section line 2—2 in Fig. 1;

Fig. 3 is a similar view taken at right angles, that is, along the section line 3—3 in Fig. 1;

Fig. 4 is a horizontal sectional view taken along the broken line 4—4 in Fig. 2 and showing in top plan the containers being advanced by the turret of the apparatus;

Fig. 5 is a face view on an enlarged scale of one set of expanding devices and showing partly in section a container and its closure member, the positions of the parts being such as to disclose the effect of the reforming or expanding operation on the closure element, parts being broken away;

Fig. 6 is an enlarged perspective view of the upper part of the closed empty container after its closure element has been treated in the present apparatus;

Fig. 7 is a transverse vertical sectional view taken along the broken line 7—7 in Fig. 4 and showing certain operating details; and

Fig. 8 is a combined section and side elevation drawn to the same scale as Fig. 7 and viewed substantially along the line 8—8 in Fig. 1, this view showing one of the expanding units, parts being broken away.

For the purpose of exemplifying the invention in a concrete form, the drawings illustrate an apparatus which may be a part of a larger machine. This apparatus is particularly adapted to treating a fiber container just after it has been fabricated. Where such a container is for holding milk as in the aforesaid Hothersall patent, the wax coating step has just been completed. Accordingly, the drawings disclose the fully formed and coated containers being brought in by a feed conveyor which may be a part of the same conveyor used to conduct the cans through the previous coating step.

To this end, Figs. 1 and 2 show a feed conveyor A which carries a series of equally spaced can cages B, each cage being adapted for holding one fiber container a having a top wall b and a hinge closure element c secured to the top as for example by a hinge staple d (see also Fig. 6). The conveyor A brings the containers a to a rotatable turret C which has a series of spaced can receiving pockets D (see also Fig. 4).

A transfer device E associated with each turret pocket D is used for lifting the container a from its cage B and for positioning it in its corresponding turret pocket. Such a transfer device thus properly locates the can within its turret pocket for the expanding operation.

This transfer of the can *a* from conveyor A to the turret C is accomplished without diminution of the can travel, the can after being received within the turret moving around a circular path of travel through about 225°. At the end of this travel it is deposited on a discharge belt F (Figs. 1 and 2). This belt removes it from the apparatus.

It is during this circular container travel that the closure element *c* is slightly reshaped to more positively hold it in closed position. As previously explained, this is a temporary securing of the parts together prior to the filling of the can. In this operation a plug part or section *e* of the closure element *c*, which extends into the filling and dispensing opening of the can, is expanded in two diametrically opposed lugs *f* (Figs. 5 and 6). These lugs extend laterally under the top wall *b* at the edge of the dispensing opening. This securely holds the closure element in its closed position, but since the lugs are small, the can may be opened easily by lifting the plug part from its seat.

The formation of the lugs *f* is effected by an expanding device *G*, best illustrated in Figs. 5 and 8. Each expanding device includes a pair of expanding fingers and there is one such device for each turret pocket. The expanding fingers are carried in the upper part of the turret assembly and above the associated turret pocket. The lower ends of the fingers are in such a position as to be received into the depressed plug section *e* of the closure *c* when the can is lifted in its pocket by the transfer and lifting device *E*. Since each container within a turret pocket has its own expanding device *G*, the different expanding operations on different containers are taking place in various stages as they traverse the 225 degrees of circular travel with the turret.

The feed conveyor A (Figs. 1 and 2) preferably consists of chain links 21 and this chain operates in a horizontal plane by passing over suitable horizontally disposed sprockets mounted on vertical shafts. This feature is shown only fragmentarily in the drawings, that part of the chain which extends into the present apparatus taking over a sprocket 22 which is mounted on a vertical shaft 23. This shaft is journaled in bearings 24, 25 formed in a casing 26 which constitutes the main frame of the apparatus.

Every other chain link 21 supports a cage B, each alternate link of the chain being used as a spacer element between two adjacent cages. The cage B comprises a vertically disposed arm 28 having at its top end a pair of laterally extending arms 29. The two arms 29 are disposed substantially at right angles to one another and retain the upper end of the container *a* in proper position within the cage. At the lower end each vertically disposed arm 28 extends down at an angle and spreads out on both sides to form a closed hollow angular base 31.

When the containers *a* come into the present apparatus each container rests upon its associated base member 31. It is disposed in an angular position, as to its base relation to the conveyor, being so held by projections 32 formed on each laterally extending finger 29 of the individual cage member. The container is in an upright position at such time, its inner corner sliding along a pair of horizontally disposed guide rails 35 which are secured to a wall 36 of the frame 26. During this straight travel of the containers with the conveyor chain, the cages B

are further supported by rollers, as best illustrated in Fig. 2.

As to this feature each cage B adjacent the top of its arm 28, carries a pin 41. A roller 42 is rotatably mounted on the pin. At the bottom, this vertical arm carries a pin 43 on which a roller 44 is rotatably mounted.

An upper grooved track 45 (see also Fig. 1) is disposed above the upper roller 42 which travels along the grooved lower edge of the track or guide rail. In a similar manner a lower track or guide rail 46 is carried on the frame of the machine and is formed in its upper surface with a groove in which the roller 44 rotates during advancement of the chain. This construction definitely retains the various cages in proper holding position and insures passage of the closed empty container *a* into the apparatus.

The rotatable turret C (Figs. 2 and 4) comprises a turret hub 51 which supports upper and lower turret plates 52. The turret pockets D are cut in the periphery of the two turret plates 52. The plate edges of the pockets are in vertical alignment to provide a proper holding surface for the container *a* which is received into the turret from the conveyor A.

The turret C is mounted on a vertical shaft 53 which is journaled at its lower end in a bearing 54 formed in the lower wall of the frame 26. The shaft adjacent its upper end is also journaled in a bearing 55 formed in a cover plate 56 which is bolted to the upper wall of the frame 26. The shaft 53 is rotated in any suitable manner in time with the rotation of the sprocket 22 over which the conveyor A moves.

As best illustrated in Fig. 1, the shaft 53 is disposed adjacent the sprocket shaft 23 but is located in rear of (that is, to the left in Fig. 1) the sprocket shaft. The turret pocket D which is shaped and disposed to receive a container *a* while it is still in the cage B is brought adjacent to a cage as the container passes into the turret pocket. This is at the position marked X in Figs. 1 and 4. It is at position X where the container is lifted from the holding cage and is transferred to the turret by means of the transfer device *E*. It is then carried by the turret in a counterclockwise direction (Figs. 1 and 4).

A stationary cam 58 surrounds the lower end of the shaft 53 (Figs. 2, 3 and 7) and is held against rotation by a bolt 59 which extends from the lower wall of the frame 26 adjacent the bearing 54 and into the cam. Just beyond the periphery of the cam 58 a series of sleeve hubs 61 are formed in the turret C and extend between the two turret plates 52. Each hub 61 incloses a vertically extending bore 62 in which a sliding rod 63 is mounted. A block 64 is fastened to the lower end of the rod and is disposed at the periphery of the stationary cam 58. This block 64 is adapted to be raised and lowered as the turret rotates at which time the rod 63 is raised and lowered in its bore 62.

Such movement of the block 64 is effected by engagement of a cam roller 65, which is rotatably mounted on a pin 66 carried in the block 64, with a cam groove 67 formed in the periphery of the stationary cam 58. As the turret C rotates each block 64 carried thereby is moved around a circular path of travel during which time its cam roller 65 traverses the cam groove 67 of the stationary cam 58.

This cam groove is formed to cause the block 64 to lift when the block passes adjacent the can transfer station X. It is this lifting move-

ment that effects the lifting of the can from its cage B. A lifting arm 68 extends laterally from each block 64 and as the arm moves up with the block its outer end engages under the bottom of the container a and lifts it into the position shown at the left in Fig. 2. The can is free of the supporting arms 31 of the cage member when in this raised position.

The shaft 53 above the turret C carries a spider 71 (Figs. 1 and 2) which is formed with a hub 72 where the spider is carried on the shaft and with a pair of concentric downwardly extending walls 73 formed adjacent the periphery of the spider. It is this spider that carries expanding devices G. An annular ring plate 74 is secured to the lower surface of the concentric walls 73 and when the container a is lifted from its cage B by raising of the arm 68, the upper or top part of the container is brought into engagement with the lower surface of the ring plate.

Following this lifting of the container into its raised position and during the continued rotation of the turret, the container is brought above a spring held segment track 75 (Figs. 4 and 7). This holds the container up against the ring plate and immediately following, the arm 68 of the raising block 64 moves back into the lower position illustrated in Fig. 7. In the continuance of this circular travel of the containers with the turret, the container is held against the plate 74 by the spring held segment track 75. A pair of circular guide rails 76 (see also Figs. 2 and 3) carried on bracket 77 mounted on the frame wall 26, maintains the containers in their turret pockets. The lower guide rail 76 also provides for a pivotal mounting of the segment track as will now be explained.

The spring track 75 is carried on the inner ends of spaced arms 78, 79 which are located on two sides of one of the brackets 77. Arm 78 is longer than the arm 79. Both arms at an equal distance from the circular track carry setscrews 81 which provide for a pivotal connection with a lug extension 82 depending from the lower guide rail 76 adjacent the bracket 77. The inner ends of the screws extend into sockets formed in the lug 82 and this allows for slight oscillation of the track 75 relative to the support.

The long arm 78 extends back of and beyond its pivotal mounting as an arm section 85 which is spaced alongside of the bracket 77. This arm section at its outer end is enlarged as at 86 to provide a base for a vertically extending rod 87 which supports a spring 88. Rod 87 projects through an opening in an auxiliary bracket 89 which is bolted to the bracket 77. Above the bracket the rod carries a locknut 91.

The pad 86 also threadedly supports a setscrew 92 and provides a stop for holding the track 75 in a definite horizontal position when the full expanding action of the spring 88 is effective. To do this the lower end of the setscrew engages a lug 93 formed in the auxiliary bracket. A locknut 94 threaded on the setscrew holds it in adjusted position so that the pressure of the spring 88 will not lift the spring track beyond a predetermined desired position. By reason of this spring support, however, the track 75 may be depressed a slight distance should a higher than normal can be in the turret pocket. This construction insures that the can a will be held against the upper ring plate 74 for the expanding operation.

The spring held segment track 75 terminates 75

just beyond the first bracket 77 and the moving container upon passing from this track engages on a second spring held segment track 101 (Fig. 4) which is identical in construction to the spring track 75 and its mounting. Accordingly track 101 is supported by a short arm 102 and a long arm 103 which carry setscrews 104 which engage in a lug 105 extending down from the lower guide rail 76 adjacent the second bracket 77.

The long arm 103 extends back alongside of the bracket and carries a spring unit mounted on a rod 106 projecting up from the arm and extending through an auxiliary bracket 107. A setscrew 108 provides for the desired stop element for the track 101. Track 101 like the spring track 75 also keeps the container in its raised position against the ring plate 74. It is while the container is in its raised position that the expanding devices G become effective. These will next be considered.

The different units of the expanding device G are all carried in the spider 71 which by reason of its close association with the turret may be considered to be broadly a part of the turret assembly. For the most part the expanding devices and expanding fingers are confined in the space between the concentric walls 73. The expanding devices are carried on shafts 111 (Figs. 1 and 5) which extend between the concentric walls. In each expanding device unit there are two adjacent shafts for supporting two expanding fingers.

On each shaft 111 and in the space between the concentric walls is mounted a split hub 112 which is adapted to be clamped in fixed position on the shaft 111 by a locknut 113. Each hub 112 is formed with a laterally extending arm 114, the two arms of the two adjacent hubs extending outwardly in opposite directions as best shown in Fig. 5.

Each arm 114 carries a pin 115 which projects outwardly beyond the outer concentric wall 73 through a clearance opening 116 cut in the wall. A cam roller 117 is rotatably mounted on each pin 115 and such cam roller is thus located out beyond the outer concentric wall.

As the individual containers a advancing in their counterclockwise travel with the turrets pass from the feed station X the two cam rollers 117 associated with that container move into cam track 121 (Figs. 1, 3 and 8) formed in a channel cam 122. This channel cam is circular in plan and is concentric with the turret shaft 53 being located just beyond the outer wall of the spider 71. It is held in a stationary position so that through about ninety degrees the cam rollers 117 traverse the cam track, and this provides for the actuation of the expanding fingers to form the holding lugs f.

The cam 122 is adjustably mounted in a manner to permit raising and lowering of the cam while maintaining its horizontal relation with the spider 71. For this purpose the middle of the cam engages against a vertical wall 125 of a bracket 126 which is secured to spacer parts 127 of the upper casing frame 26. This mounting of the cam on the bracket 126 is in between the two guide track brackets 77 as best shown in Fig. 1.

The cam is formed with a downwardly extending arm 128 which is adapted to be held securely on the bracket wall 125. Arm 128 is formed with a vertically disposed bore 129 which is internally threaded to provide for an

adjusting bolt 131. The bolt 131 is formed with parallel collar sections 132 which rotatably engage a block 133 bolted at 134 to the lower end of the bracket extension 125. By turning the adjusting bolt 131 the cam 122 may be raised and lowered according to the direction of its rotation.

After the cam has been adjusted to its desired vertical position it is locked in place by a locking bolt 135 which extends through a slot 136 cut in the bracket wall 125, the bolt head resting against a washer when the bolt is screwed tight. The stem of the bolt is threadedly engaged in the cam extension 128. By means of this construction the cam 122 is adjusted to a desired horizontal position in order to provide for the proper operating effect upon the expanding device G as it passes along this cam track.

Each hub 112 (Fig. 5) is extended downwardly at 141 to provide for support of an expanding finger 142. There is a finger 142 for each of the two hub members 112 in each individual expanding device G and each finger is held in position by a block 143 which is bolted against the finger, the bolt passing through an opening in the block and having threaded connection with the extension 141.

When the transfer device E lifts the container to its raised position against the ring plate 74 30 it positions the plug section e of the closure element c over the ends of the two adjacent fingers 142. These fingers at such time are in collapsed position, that is, in a position nearest to each other. When the container reaches its raised position the lower surfaces of the expanding fingers 142 just clear the top of the depressed plug section e of the can closure element.

As the container is advanced along its circular path of travel, the cam rollers 117 of the expanding device G pass through a raised section of the cam track and this swings each of the arms 114 so that the two fingers 142 are separated or forced outwardly into the position shown in Fig. 5. In moving into this position the vertical wall of the depressed plug section e is forced outwardly and the lugs f are thus formed on opposite sides in the closure element.

As soon as the lugs have thus been formed the expanding unit continuing along the circular path of travel causes the cam rollers 117 to traverse a lowered section of the cam track and the expanding unit is thus moved back into its collapsed position. The two fingers 142 moving in thus free the walls of the closure elements.

After this expanding operation has taken place and as the closed can a continues on in its circular path of travel it reaches the end of the spring pressed track 101. Just before dropping off of this track it passes above a circular track segment 145 (Figs. 2 and 4) which is disposed below the path of travel of the cans and upon reaching the end of the spring pressed track 101, the can drops down to the lower level and then continues on over the segmental track 145.

Track segment 145 is mounted upon a pair of arms 146 which extend outwardly from a bracket 147. This bracket is mounted on a block 148 which is carried on the lower wall of the frame 26. The bracket 147 also provides support for the discharge ends of the two guide rails 76. In dropping to this lower

level the container is entirely freed from the spider 71 and spider ring plate 74 and from the expanding units G and in such lowered position continues its travel toward the discharge belt F.

The track 145 and also the guide rails 76 extend out into a straight section at the discharge end of the machine so that as the can bodies approach the discharge belt F they are diverted from their circular path of travel and are removed from the turret pockets. This removal of a can from the turret pocket is accomplished by cooperation with a straight inner guide rail 149 (Fig. 1) which is carried in the frame of the machine and which extends parallel to a straight section of the guide rails 76. The track 145 as well as the guide rails 76 and 149 extend to a position adjacent the discharge belt and the containers are guided onto the discharge belt. The belt removes them from the machine.

The discharge belt F in the present apparatus takes over a carry-off pulley 151 (Figs. 1 and 2) which is mounted on a horizontal shaft 152 journaled in bearings 153 formed in the frame 26. The shaft 152 may be rotated in any suitable manner to provide for the proper travel of the discharge belt so that the containers are removed from the machine as succeeding containers are discharged from the turret.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for handling a fiber container having a closure element hingedly mounted on the top wall thereof and which is in an inserted position in an opening in said wall, the combination of mechanism for advancing a said container along a predetermined path of travel through the machine, means for supporting said container as it is so advanced, and means operative during the advancement of the container by

50 said advancing mechanism for expanding beneath the container top wall a restricted portion of that part of the closure wall which extends into the opening of said container to temporarily retain said closure element in closed position on the container, said container supporting means having a spring pressed mounting to compensate for fiber containers of slightly varying heights and to prevent crushing and damage thereto during the expanding operation.

2. In a machine for handling a fiber container having a closure element hingedly mounted on the top wall thereof and which is in an inserted position in an opening in said wall, the combination of a rotatable turret for advancing 65 a said container along a predetermined path of travel through the machine, means for supporting said container during such advancement, and means carried by said turret and operative during the advancement of the container by said turret for expanding beneath the container top wall a restricted portion of that part of the closure wall which extends into the opening of said container to temporarily retain said closure element in closed position on the container, said container supporting means having a spring

pressed mounting to compensate for fiber containers of slightly varying heights and to prevent crushing and damage thereto during the expanding operation.

3. In a machine for handling a fiber container having a closure element hingedly mounted on the top wall thereof and which is in an inserted position in an opening in said wall, the combination of a rotatable turret having a peripheral pocket for advancing a said container along a predetermined path of travel through the machine, a feed conveyor for bringing the containers into said turret, transfer means for engaging said container on said feed conveyor and elevating the same therefrom into said turret pocket, and expanding means carried by said turret and operative during the advancement of the container by said turret for pressing out a part of the closure wall which extends into the opening formed in said container top wall at two opposite points in order to engage the closure element under the container top wall to temporarily retain said closure element in closed position for subsequent operation on the container.

4. In a machine for handling a fiber container having a closure element hingedly mounted on the top wall thereof and which is in an inserted position in an opening in said wall, the combination of a rotatable turret having peripherally disposed container receiving pockets for holding and for advancing the containers in a circular path of travel, means adjacent said turret for supporting the containers as the same are advanced, expanding finger units carried by said turret with a said unit disposed above each turret pocket, each of said units being adapted to extend into the said closure element of the container which is being carried within its corresponding turret pocket, and means for moving said finger units to expand beneath the container top wall a restricted portion of that part of the closure wall which extends into the opening of said container to temporarily retain said closure element in closed position on the container, said container supporting means having a spring pressed mounting to compensate for fiber containers of slightly varying heights and to prevent crushing and damage thereto during the expanding operation.

5. In a machine for handling a fiber container

having a closure element hingedly mounted on the top wall thereof and which is in an inserted position in an opening in said wall, the combination of a rotatable turret having container receiving pockets for holding and for advancing the containers in a circular path of travel, a track disposed adjacent said turret for supporting said containers as the same are advanced, expanding finger units carried by said turret with a said unit disposed above each turret pocket, each of said units comprising a pair of fingers which are adapted to extend into the said closure element of the container which is being carried within its corresponding turret pocket, and means for separating the two fingers in each finger unit so as to expand beneath the container top wall two opposed restricted portions of that part of the closure wall which extends into the opening of said container to temporarily retain said closure element in closed position on the container, said container supporting track having a yieldable spring pressed mounting to compensate for fiber containers of slightly varying heights and to prevent crushing and damage thereto while the expanding operation is performed on said closure element.

6. In a machine for handling a fiber container having a closure element hingedly mounted on the top wall thereof and which is in an inserted position in an opening in said wall, the combination of a rotatable turret having container receiving pockets for holding and for advancing the containers in a circular path of travel, a feed conveyor having container holding cage members for bringing a container which has been deposited in a said cage member adjacent to said turret, transfer devices for lifting a container out of its cage member and for positioning it into a said turret pocket, a pair of expanding fingers pivotally carried by said turret above each of its pockets which extend into the closure element of its pocketed container as soon as such container is positioned in the turret pocket by said transfer devices, and cam means for rocking each pair of fingers on said pivotal mounting to expand the said closure element at the two opposite points to engage under the container top wall to temporarily retain the closure element in closed position.

LLEWELLYN BIGGS.
